UNITED STATES PATENT OFFICE

HARRY A. HIGGINS, OF DETROIT, MICHIGAN

RADIATOR

Application filed March 29, 1926. Serial No. 98,395.

This invention relates to radiators and more particularly to that character of radiator known as the vertical water tube type.

The invention has among its objects to improve generally devices of this character by simplifying and consequently cheapening the cost of manufacture and at the same time maintaining a high degree of efficiency. The several objects of the invention as well as various advantages and novel details of construction will be made more apparent as this description proceeds, especially when considered in connection with the accompanying drawings wherein;

15 Figure 1 is a front elevational view of a radiator constructed in accordance with this invention;

Figure 2 is a detail end elevational view of two of the tube sheets removed, and

20 Figure 3 is an enlarged fragmentary view partly in section and partly in elevation taken substantially on the plane indicated by line 3—3 of Figure 1.

Referring now particularly to Figures 1 to 25 3 of the drawing, it will be noted that there is illustrated a radiator including upper and lower headers 10 and 11 adapted to be connected by a plurality of water tubes 12 herein shown as comprising flat hollow members shaped to simulate a plurality of vertical tubes.

Each flat tubular member or radiator section 12 consists essentially of two sides or sheets 13 arranged in spaced parallel relation and as the construction is shown, each section may be formed by employing two separate sheets united at their vertical edges as indicated at 14. Each member may however be formed from a single sheet of material bent longitudinally thereof and having its free longitudinal edges united as is well known in this art.

Each sheet 13 is shaped to provide a plurality of vertically extending spaced ribs 15, the ribs on the opposed sheets 13 coinciding so that when the sheets 13 are assembled these ribs will be arranged in abutting relation, thus spacing the sheets apart as clearly illustrated in Figure 2 and defining or simulating a plurality of vertically extending

water tubes or passages 16. The upper and lower ends of the sections 12 are connected to the headers 10 and 11 in any well known manner such for instance as suggested in Figure 3 by extending the adjacent end of 55 the section through a suitably shaped aperture in the wall of the header and soldering the same along the joint such as indicated at 17.

Each of the tube sheets or sections 12 is 60 formed with a plurality of outwardly extending rib like protuberances 18 which extend transversely of the sheets 13. These outwardly extending protuberances interrupt the vertically extending ribs 15 at the points at 65 which they intercept these ribs. While any desired contour may be effected in these ribs they are herein shown as curved laterally out of their general direction it being preferable however that all of the ribs be similarly 70 shaped and uniformly spaced so that when assembling the radiator the corresponding ribs on adjacent radiator sections 12 may be caused to abut to thus space the radiator sections and to provide air passages A between 75 the radiator sections extending from the front toward the rear thereof. By forming the ribs of a curved contour such as herein illustrated the direct passage of air between the sections of the radiator is prevented and a 80 more intimate contact between the air and radiator sections is attained. The adjacent sections 12 of the radiator in the assembled position of the parts may be united as for instance by soldering the same together at the 85 abutting portions of the ribs or protuberances 18. Furthermore, inasmuch as these protuberances extend outwardly from the sheet and the recesses formed thereby communicate with the interior of the sections 12 the water 90 contained therein is subjected to the direct heat dissipating effects of the air.

In constructing radiators in accordance with this present invention the tube sheets or radiator sections may be quickly and 95 cheaply manufactured out of sheet metal by a stamping operation to form the outwardly extending rib like protuberances, having any desired configuration or form. When there- 100 after a plurality of sections are assembled in

connection with the radiator frame and the upper and lower headers the opposed protuberances of adjacent sections are brought into abutting contact and serve not only to 5 properly space and align the radiator sections, but also to form tortuous air directing passages between the sections. By stamping these protuberances outwardly from the walls of the sections laterally directed water chambers are produced which extend into the path 10 of the air to increase the heat dissipating efficiency of the apparatus. As suggested in Figures 1 to 3 each section may be additionally provided with inwardly directed ribs or 15 protuberances providing spacing means for the walls of each section to insure against the collapsing of the sections. Also in such a construction these vertically disposed ribs or protuberances define vertical water passages 20 for directing and distributing the water throughout the thickness of the radiator to further insure efficient heat dissipation.

While the invention has been described somewhat in detail in connection with several 25 modifications of the same it will be readily apparent that the invention is capable of expression in various other forms and to this end reservation is made to make such changes in details of construction as may come within 30 the purview of the accompanying claims.

What I claim as my invention is:

1. A radiator formed of sections, each comprising a pair of plates arranged parallel to each other and connected together at their 35 vertical edges to form a water passage therebetween, inwardly extending protuberances formed in said plates, opposed protuberances abutting and outwardly directed, longitudinally curved protuberances formed in said 40 plates for spacing adjacent sections and defining tortuous air passages between said sections.

2. A radiator formed of sections, each comprising a pair of plates arranged parallel to each other and connected together at their 45 vertical edges to form a water passage therebetween, inwardly extending protuberances formed in said plates and outwardly extending longitudinally curved protuberances 50 formed in said plates, the opposed inwardly extending protuberances of adjacent plates abutting and the opposed outwardly extending protuberances of adjacent sections abutting.

55 3. A radiator formed of sections, each comprising a pair of plates arranged parallel to each other and connected together at their vertical edges to form a water passage therebetween, inwardly extending protuberances 60 formed in said plates and outwardly extending protuberances formed in said plates and shaped to form tortuous air passages between said sections.

4. A radiator formed of sections, each comprising a substantially flat compartment con-

stituting a water chamber with the opposed walls thereof shaped to form a plurality of spaced inwardly extending protuberances extending from the top to the bottom of the radiator and abutting to space said walls, and 70 with a plurality of outwardly extending protuberances arranged to abut the corresponding protuberances of the next adjacent section and to form continuous air passages between said sections. 75

5. A radiator formed of sections, each comprising a substantially flat compartment constituting a water chamber with the opposed walls thereof shaped to form a plurality of spaced inwardly extending protuberances 80 abutting to space said walls and to divide said water chamber into vertical water passages and provided further with a plurality of outwardly extending protuberances arranged to abut the corresponding protuberances of the 85 next adjacent section, the said outwardly extending protuberances forming horizontally arranged air and water passages between said sections.

6. A radiator formed of sections, each comprising a pair of plates arranged parallel to each other and connected together at their vertical edges to form a water passage therebetween, inwardly extending abutting protuberances in said plates dividing said water 90 passage into a plurality of spaced passages and outwardly extending protuberances in said plates forming tortuous air and water 95 passages between said sections and at an angle to said first mentioned water passages.

100 7. A radiator formed of sections, each comprising a pair of plates arranged parallel to each other and connected together at their vertical edges to form a water passage therebetween, inwardly extending protuberances in said plates dividing said water passage into a plurality of spaced passages and outwardly extending protuberances formed in said plates, spaced to abut the corresponding 105 protuberances on the adjacent section and longitudinally curved to form tortuous water passages angularly arranged with respect to said first mentioned water passages and tortuous air passages between said sections.

110 In testimony whereof I affix my signature. 115
HARRY A. HIGGINS.
